UNITED STATES PATENT OFFICE.

LOUIS JONCAS, OF AUBURN, MAINE.

SEAM-PRESSING MACHINE.

SPECIFICATION forming part of Letters Patent No. 443,917, dated December 30, 1890.

Application filed December 11, 1889. Serial No. 333,335. (No model.)

To all whom it may concern:

Be it known that I, LOUIS JONCAS, a citizen of the United States of America, residing at Auburn, in the county of Androscoggin and 5 State of Maine, have invented certain new and useful Improvements in Devices for Pressing Gore-Seams for Congress-Shoe Uppers; and I do hereby declare the following to be a full, clear, and exact description of the invention, 10 such as will enable others skilled in the art to which it appertains to make and use the same.

My invention relates to the manufacture of uppers for "Congress boots," so called. In the manufacture of these uppers the elastic gores 15 are glued or pasted to the adjusting parts of the upper, the leather being turned or folded over to form a flat seam or joint previous to being stitched. This is done by applying paste to the edges, placing the gore, the lining, and 20 the leather portion of the upper in proper position, and then pressing the same by applying thereto a weight until the paste adheres. The uppers are then removed and weights are placed upon the seams for a limited length of 25 time until they have become dry enough to remain in place.

My invention has for its object the construction of a simple and effective machine for retaining the gores in place during the operation of cementing and for compressing the 30 seams after the same have been cemented by the use of a heavy mechanical pressure.

The several parts of my device as I have herein shown it are a flat base or table, a 35 pair of properly-formed pressing-levers pivoted at one end to said base, and a link and eccentric for pressing the opposite end toward said table.

Means are provided for the adjustment of 40 the several parts to exert a greater or less pressure upon the same or to provide for varying thicknesses.

My invention in the form in which I prefer to embody it is shown in the accompanying drawings, in which—

Figure 1 is a plan or top view; Fig. 2, a longitudinal section through x of Fig. 1. Fig. 3 is a front elevation; Fig. 4, a view of the upper as fitted for being placed in my machine.

50 The base rests upon suitable legs or supports a , and is here shown as hollow with a flat upper surface. If desired, steam may be

admitted into the hollow base. (Not here illustrated.)

To one end of the base A are adjustably 55 screwed two brackets b by means of the bolts b' , passing through vertical slots b^3 . The lower end of the bracket b extends beneath the bed A , and an adjusting-screw b^2 passes up through this portion and impinges on the 60 under side of the bed A . The height of the bracket b is thus regulated by the screw b^2 . Pivoted to lugs on the upper end of the bracket b are two pressing-levers B , which extend the entire length of the bed or base A . These 65 levers are tapering in form and are of such size and relative position that they will press uniformly on the seams of both gores in the upper when the latter is placed beneath them.

On the free end of each of the levers B and 70 extending somewhat beyond the end is an adjusting-arm C , pivoted to a lug c on the top of the pressing-lever B .

Means are provided for sustaining the adjusting-arm C at varying heights, here shown 75 as adjusting-screws c' and c^2 , one of which passes through the lever B and the adjusting-arm C , and the other passes through the adjusting arm C and impinges on the top of the lever-arm B . Means are also provided for 80 forcing down the free ends of the pressing-levers B , as hereinafter shown. The extreme end of the adjusting-arm C is bifurcated, and in the top of each bifurcation is a notch c^3 , in which fits the cross-head d , attached to 85 the upper end of the link D . The lower end of link D is pivoted to an eccentric e , by which it is forced downward. An arbor E , journaled in bearings, connects the two eccentrics e . A lever e^2 is provided for turning 90 the arbor E to raise and lower said links. The two links D are connected by means of a connecting-rod e' , which extends from one to the other.

H represents the upper; h , the gores, and 95 h' the gore-seams.

The operation of my device is evident from its construction. When it is desired to press the seams of the gore, the two pressing-levers B are raised or tilted back, the links having 100 been released from their ends and tilted forward. The upper is then placed in position on the bed A , the gore-seams lying substantially parallel with the edges of the pressing-

levers B. The levers are then lowered to rest upon the gore-seams, and the links D are raised by means of the lever c^2 , the cross-heads made to engage the notches c^3 , and they are then forced downward by the lever c^2 , holding the uppers in place and exerting a heavy pressure upon the gore-seams h' . When the seams have been sufficiently pressed and the glue or paste sufficiently hardened, the link D is released from the end of the arm C, the pressing-levers raised, and the upper removed.

It will be seen that my device can be quickly operated and that it may be readily adjusted for varying thickness of uppers and varying degrees of pressure, as desired.

The gore-seams formed by the use of my machine are more firm, compact, and flat than those hitherto formed by use of ordinary 20 weights.

I claim—

1. In a device for pressing gore-seams of boots and shoes, the combination of a bed or table, a pressing-lever pivoted by one end 25 thereto and having its lower face substantially parallel with the said bed when resting on the seam to be pressed, a latch or link adapted to be engaged and disengaged from

the free end of the lever, and an eccentric for depressing said link, substantially as de- 30 scribed.

2. In a device for pressing the gore-seams of boots and shoes, the combination of a bed or table, a pressing-lever pivoted to one end of the same, an adjusting-arm pivoted to said lever and adapted to be held in various positions, and means for applying force to said adjusting-arm to depress said lever, substantially as described.

3. In a device for pressing gore-seams of 40 shoes, the combination of a base or table, a pressing-lever for pressing the gore-seam pivoted by one end thereto, an adjusting-arm pivoted on the top of said lever and having its free end extending beyond the end of said 45 lever, a link for engaging the free end of said adjusting-arm, an eccentric to which said link is pivoted, and a lever for rotating said eccentrics to raise and lower said link, substantially as shown.

In testimony whereof I affix my signature in presence of two witnesses.

LOUIS JONCAS.
